STOCKING

Jon Wallner, Jr., Clinton, Tenn., assignor to Magnet Mills,
Inc., New York, N.Y., a corporation of New York

Filed Aug. 5, 1965, Ser. No. 86,453

Term of patent 14 years

(Cl. D47—7)

FIG. 1 is a side elevational view of stocking showing my new design, the side opposite being a mirror image thereof; and

FIG. 2 is a fragmentary enlargement of the decorative detail shown in FIG. 1, the balance of the stocking being of a conventional appearance.

I claim:

The ornamental design for a stocking, as shown and described.
